(57) **CLAIM**

The ornamental design for a door lite frame, as shown and described.

DESCRIPTION

FIG. 1 is a front elevational view of our design, with the dotted lines indicating environment;

FIG. 2 is a front elevational view of our design;

FIG. 3 is a cross-sectional view taken along the line 3—3 of FIG. 2 and viewed in the direction of the arrows;

FIG. 4 is a cross-sectional view taken along the line 4—4 of FIG. 2 and viewed in the direction of the arrows;

FIG. 5 is an enlarged cross-sectional view taken along the line 5—5 of FIG. 2 and viewed in the direction of the arrows; and

FIG. 6 is a front elevational view a second embodiment of our design, with the cross-sectional view of FIG. 5 showing the shape; and,

FIG. 7 is a cross-sectional view taken along the line 7—7 of FIG. 6 and viewed in the direction of the arrows.
